[57] **CLAIM**

The ornamental design for a base for cooking vessel, as shown and described.

DESCRIPTION

FIG. 1 is a top, side and end perspective view of a base for cooking vessel showing my new design;

FIG. 2 is an end elevation view thereof, the opposite end elevation being the same;

FIG. 3 is a side elevation view thereof, the opposite side elevation being the same;

FIG. 4 is a top plan view thereof;

FIG. 5 is a bottom plan view thereof;

FIG. 6 is a top, side and end perspective view of a variation of my new design;

FIG. 7 is an end elevation view thereof, the opposite end elevation being the same;

FIG. 8 is a side elevation view thereof, the opposite side elevation being the same;

FIG. 9 is a top plan view thereof;

FIG. 10 is a bottom plan view thereof;

FIG. 11 is a top, side and end perspective view of a second variation of my new design;

FIG. 12 is an end elevation view thereof, the opposite end elevation being the same;

FIG. 13 is a side elevational view thereof, the opposite side elevation being the same;

FIG. 14 is a top plan view thereof;

FIG. 15 is a bottom plan view thereof;

FIG. 16 is a top, side and end perspective view of a third variation of my new design;

FIG. 17 is an end elevation view thereof, the opposite end elevation being the same;

FIG. 18 is a side elevation view thereof, the opposite side elevation being the same;

FIG. 19 is a top plan view thereof; and,

FIG. 20 is a bottom plan view thereof.
